UNITED STATES PATENT OFFICE.

CHARLES W. AMES, OF EYEBROW, SASKATCHEWAN, CANADA.

GRAIN-SHOCKER.

1,357,537.

Specification of Letters Patent. Patented Nov. 2, 1920.

Application filed September 18, 1918. Serial No. 254,665.

To all whom it may concern:

Be it known that I, CHARLES W. AMES, a subject of the King of Great Britain, residing at Eyebrow, in the Province of Saskatchewan and Dominion of Canada, have invented certain new and useful Improvements in Grain-Shockers; and I do hereby declare the following to be a full, clear, and exact description of the invention, such as will enable others skilled in the art to which it appertains to make and use the same.

The object of the invention is to provide a practical and efficient grain shocking mechanism adapted to receive the bundles from the harvester during the progress of the latter and after a sufficient number of bundles have been accumulated to form a shock to deposit the latter in an upright position upon the ground, the body of the shock being compressed so that it may be properly secured and retained until such time as it may be suitable to remove it to the barn or other point of deposit, and a further object of the invention is to provide means for the indicated purpose which may be controlled with the minimum effort upon the part of the operator and the minimum disturbance of the shock in the removal of the machine therefrom after it has been deposited as indicated upon the ground.

Further objects and advantages will appear in the course of the following description, it being understood that changes in form, proportion and details may be resorted to, within the scope of the appended claims, without departing from the spirit of the invention.

In the drawings:

Figure 1 is a side view of a machine embodying the invention, the near ground or supporting wheel being omitted and shown in dotted lines.

Fig. 2 is a front view of the same.

Fig. 3 is a front view showing the parts in the dumping or shock depositing positions.

Fig. 4 is a side view showing the guard fork and connections in the depressed or dumping position, the receptacle being indicated in dotted lines in the related position.

Fig. 5 is a detail sectional view of a portion of the machine to show the gearing and clutch mechanism by which the movement of the shock forming receptacle is controlled.

In the illustrated embodiment of the in-

vention the main frame 10, having side bars or members connected at their front ends by a cross bar 11 and at their rear ends by an arch 12, is supported by ground wheels 13 mounted upon stub axles 14, while in bearings 16 arranged at opposite sides upon the main frame are mounted the spindles 17 of a tilting receptacle 18 enlarged toward its outlet end and adapted to receive the bundles which are to constitute the shock, said spindles 17 forming the axis upon which the receptacle is adapted to tilt from the normal position indicated in Fig. 1 to the discharging position indicated in Figs. 3 and 4.

Mounted in coöperative and tilting relation with the receptacle is a guard fork having a head 19 provided with tines 20 which in the normal or receiving position of the receptacle serve to span and close the open discharging end thereof, and supporting 70 arms 21 which extend longitudinally of the receptacle and are slotted as at 22 to receive the spindles 17 of said receptacle so that while the fork has a tilting movement with the receptacle it is also capable of a longitudinal movement relative to the receptacle as hereinafter explained. A brace rod 23 is shown extending from an intermediate portion of each supporting arm 21 to the head of the fork to stiffen the structure. 85

The receptacle at each side is provided with a fork returning or replacing arm 24 having a laterally projecting pin 25 and in connection with this fork returning pin there is arranged a spring catch 26 consisting of yielding jaws arranged in the path of said pin and adapted to engage the latter when the receptacle and fork are in their normal or loading positions. 90

Also carried by the fork is a guide arm 95 27 provided with a terminal pin 28, preferably having an anti-friction sleeve or roller 29 mounted thereon, said pin being adapted to traverse a curved dumping track 30 which is arranged in a bracket 31 depending from the side bar of the main supporting frame and arranged concentric or approximately concentric with the axis of the receptacle so that as the latter swings from its normal position to the dumping position shown in 100 dotted lines in Fig. 4, said guide pin 28 traverses the track 30 and the fork head retains its position relatively to the mouth or open end of the receptacle so as to retain the bundles in the latter. However, said 105 110

track 30 terminates short of the limit of movement of said fork and of the back of the bracket 31, and when the guide pin 28 reaches the limit of said track it drops and thus permits the fork to drop until the guide pin is checked by a lower or replacing track 32 forming a part of said bracket 31, or said fork comes in contact with the ground as shown in Figs. 3 and 4. The track 30 which may be referred to hereinafter as the dumping track for the reason that the guide 28 traverses the same during the dumping movement of the fork and receptacle, is pivotally mounted at 33 and bears at its free end upon the front side of the bracket 31 as shown at 34 and though the guide pin 28 will pass to the dumping track during the downward or dumping movement of the fork, when the fork is raised to its normal position by the contact of the pin 25 with the supporting arm 21 due to the return of the pan to the receiving or normal position, the guide pin 28 will traverse the return track 32 and in passing the free end of the dumping track will displace the free end of the latter as shown by the dotted lines in Fig. 4. Obviously, after the guide pin has passed the free end of the dumping track the latter will return to its normal position so as to properly guide said pin during the succeeding downward movement incident to a later dumping action of the fork and receptacle.

The action of the fork and receptacle therefore may be described as involving a swinging or pivotal movement thereof, the positions thereof being relatively retained, with the fork head closing the mouth or open end of the receptacle, until the latter reaches substantially a vertical position whereupon the fork will drop abruptly until checked, as above noted, by the contact of the fork head with the ground or the contact of the guide pin 28 with the return track 32, thus forcibly depositing the shock upon the ground and firmly seating it in an upright position with all of the stalk butts on the ground or settled to a proper position, and as the receptacle is moved in its return operation it will carry with it the fork which by reason of the guide track 32 is returned to its proper position relative to the receptacle the guide pin 28 being carried beyond the free end of the dumping track 30, and said fork being locked with the receptacle in the receiving position by the engagement of the pin 25 with the catch or clamp 26.

It is desirable to forcibly compress the stalks in the receptacle during the dumping operation so as to render the shock compact and reduce it at the upper portion to insure a stable seating upon the ground, and to this end there are employed side compressor arms 35 pivoted as at 36 to the fork head and having pivotally mounted elements 37

yieldingly held in proper relation with the compressor arms by springs 38 and carrying between said elements a compressor band or strap 39, the latter being adjustably connected with the elements 37 to provide for variation to suit different heights or lengths of stalks, and a similar adjustment being provided at 40 for the pivotal connection between said elements and the compressor arms. Connected with the compressor arms are guide arms 41, slotted as shown at 42 for the reception of guide pins 43, preferably provided with anti-friction sleeves or rollers 44, said guide pins being carried by bracket arms 45 rising from the main frame 10. As the fork is swung from the normal position indicated in Fig. 1 to the dumping position indicated in Figs. 3 and 4, the compressor arms, by reason of the co-operative action of the slotted guide arms 41 and the pins 43, are swung inwardly toward the pan to bring the compressor strap or band 39 into shock compressing relation with the top of the receptacle, said pivotal yielding elements 37 which carry the strap or band 39 swinging into the receptacle as indicated in Figs. 3 and 4. Obviously, this compressor mechanism is restored to its normal position by the return of the fork and receptacle to the normal or receiving position and thus disposed out of the way to avoid interfering with the deposit of the stalks in the receptacle in the course of forming the shock.

Various means may be employed for moving the receptacle and fork from the normal to the dumping position and returning the same, but for the present purposes it has been deemed sufficient to show the stub axle and spindle at one side of the machine provided with sprocket wheels 46 and 47 connected by a chain 48 for moving the receptacle and fork in one direction and the gears 49 and 50 in mesh to move the said parts in the opposite direction, a clutch being arranged between the sprocket wheel 46 and the gear wheel 49 and having its movable or shiftable member 51 keyed upon the axle as shown at 52 and adapted for engagement with either the sprocket wheel or said gear. Any suitable means may be employed for conveniently shifting this clutch member as required by the operation of the mechanism.

Also any desired form of elevator or conveyor may be employed to conduct the bundles of grain to the pan from the binder (not shown) such as that shown in my former Patent #1,233,955, and indicated in dotted lines in the drawings hereof. (See Fig. 2.)

Having described the invention, I claim:

1. A shocking mechanism having a tilting shock forming receptacle, a fork having a head for closing the discharge end of the receptacle and provided with slotted sup-

porting arms mounted coaxially with the receptacle, a guiding track disposed concentric with the axis of the receptacle for traverse by a guiding element on the fork, said track terminating short of the limit of tilting movement of the fork to release the latter for movement longitudinally of the receptacle, and means for restoring the receptacle and fork to their normal positions.

10 2. A shocking mechanism having a shock forming receptacle, spindles secured to said receptacle and rockably supporting the same, a fork having a head for closing the discharge end of the receptacle and provided 15 with slotted supporting arms slidably engaging the spindles of the receptacle for rocking movement therewith, a dumping track disposed concentrically to the axis of the receptacle, a guide pin carried by the fork 20 for traversing said track during the tilting movement of the receptacle, and releasable from said track at the limit of the tilting movement of the receptacle, a return track eccentric with the axis of the receptacle for 25 traversing by said guide pin during the return movement of the fork, and means for imparting tilting movement to said receptacle and fork.

3. A shocking mechanism having a tilting shock forming receptacle provided with spindles, a fork having a head for normally closing the discharge end of the receptacle and provided with supporting arms having slots mounted upon said receptacle spindles, 35 dumping and return tracks disposed respectively concentric with and eccentric to the axis of the receptacle, guide pins carried by the fork for traversing said tracks respectively during the dumping and return movements of the fork, the concentric dumping track terminating at one end short of the limit of dumping movement of the fork and displaceable at the opposite end by the return movement of said pin, and means for 40 imparting tilting movement to said receptacle and fork.

4. A shocking mechanism having a tilting shock forming receptacle, a fork having a head for normally closing the discharge end 45 of the receptacle and provided with slotted supporting arms mounted coaxially with the receptacle, dumping and return tracks disposed respectively concentric with and eccentric to the axis of the receptacle, a guide pin 50 carried by the fork for traversing said track successively during the dumping and re-

turn movements of the fork, the dumping track being pivotally mounted at one end short of the limit of dumping movement of the fork to release said guide pin to permit 60 downward movement of the fork, and said dumping track being yieldingly disposed at the opposite end in the path of the return movement of said guide pin, a return pin carried by the receptacle for engagement 65 with one of said supporting arms to return the fork to normal position coincidentally with the return of the receptacle, a clamp for engaging said return pin when the receptacle reaches its normal position, and means 70 for imparting tilting movement to the receptacle.

5. A shocking mechanism having a tilting shock forming receptacle, a receptacle closing fork mounted for longitudinal movement relative to the receptacle, means for guiding the fork during the dumping and return movements thereof, shock compressing mechanism having compressor arms pivotally connected with said fork head, a compressor band connecting said arms, a fixed guide, guide arms connected with the compressor arms and having sliding and tilting movement relative to said fixed guide, and means for imparting dumping and return 85 tilting movements to said pan and fork.

6. A shocking mechanism having a tilting shock forming receptacle, a fork having a head for closing the discharge end of the receptacle and provided with arms having a 90 sliding movement with reference to the axis of said receptacle, guiding means for the fork including dumping and return tracks and means for traversing the same, compressor mechanism having compressor arms provided with pivotal yielding elements connected by a compressor band or strap for engaging a shock in the receptacle, and actuating means for said compressor arm consisting of slotted guide arms and a fixed 95 guide pin engaging the same to move the compressor arms toward the receptacle during the tilting movement of the latter, and means for imparting tilting and return pivotal movements to said receptacle and fork. 100 105

In testimony whereof I affix my signature in presence of two witnesses.
